US00D646263S

(12) **United States Design Patent**
Yuan et al.

(10) **Patent No.:** US D646,263 S
(45) **Date of Patent:** ** Oct. 4, 2011

(54) **WIRELESS TRANSMITTER**

(75) Inventors: **Xiaotao Yuan**, Shenzhen (CN); **Qian Zhang**, Shenzhen (CN); **Hongyan Lu**, Shenzhen (CN)

(73) Assignee: **Muqun Cao**, Shenzhen (CN)

(**) Term: **14 Years**

(21) Appl. No.: **29/369,154**

(22) Filed: **Sep. 2, 2010**

(30) **Foreign Application Priority Data**

Jul. 29, 2010 (CN) 2010 3 0254576

(51) **LOC (9) Cl.** **14-01**

(52) **U.S. Cl.** **D14/229**; D14/224

(57) **CLAIM**

The ornamental design for a “wireless transmitter,” as shown and described.

DESCRIPTION

FIG. 1 is a perspective view of a “wireless transmitter” of the present invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines form no part of the claimed design.
